COMBINED HOLDER FOR PAD AND MEMORANDUM SHEETS

Morton M. Rodbell, New York, N. Y.

Application April 6, 1950, Serial No. 9,020

Term of patent 14 years

(Cl. D74—1)

To all whom it may concern:

Be it known that I, Morton M. Rodbell, a citizen of the United States of America, residing at 545 West End Avenue, in the city, county and State of New York, have invented a new, original, and ornamental Design for a Combined Holder for Pad and Memorandum Sheets, of which the following is a specification, reference being had to the accompanying drawing, forming part hereof, in which:

Figure 1 is the front perspective view of the combined holder for pad and memorandum sheets showing my new design with the pad holding tab in an open position.

Figure 2 is a front perspective view of the same with the pad holding tab folded up.

Figure 3 is a vertical sectional view of the same taken on line 3—3 of Figure 1.

I claim:

The ornamental design for a combined holder for pad and memorandum sheets, as shown.

MORTON M. RODBELL.
